(57) **CLAIM**

The ornamental design for a swimsuit, as shown and described.

DESCRIPTION

FIG. 1 is a front view of a swimsuit that has the design. FIG. 2 is a back view of the swimsuit that has the design. FIG. 3 is a front view of a first embodiment of the design, in the bottom portion of the swimsuit of FIGS. 1 and 2, in a closed configuration.

FIG. 4 is a front view of the first embodiment of the design, in the bottom portion of the swimsuit of FIGS. 1 and 2, in an open configuration.

FIG. 5 is a front view of a second embodiment of the design, in the bottom portion of the swimsuit of FIGS. 1 and 2, in a closed configuration.

FIG. 6 is a front view of the second embodiment of the design, in the bottom portion of the swimsuit of FIGS. 1 and 2, in an open configuration.

FIG. 7 is a front view of a third embodiment of the design, in the bottom portion of the swimsuit of FIGS. 1 and 2, in a closed configuration; and,

FIG. 8 is a front view of the third embodiment of the design, in the bottom portion of the swimsuit of FIGS. 1 and 2, in an open configuration.

The broken lines show elements of the swimsuit that form no part of the claimed design.

1 Claim, 4 Drawing Sheets
